UNITED STATES PATENT OFFICE.

SAMUEL EDWARD MOORE, OF HARRISBURG, PENNSYLVANIA, ASSIGNOR OF ONE-FOURTH TO JAMES MCKIRDY, OF CARLISLE, PENNSYLVANIA, AND ONE-FOURTH TO FRANK M. EASTMAN, OF HARRISBURG, PENNSYLVANIA.

INDEX-DRAWER.

1,227,172.

Specification of Letters Patent. Patented May 22, 1917.

Application filed August 12, 1916. Serial No. 114,576.

To all whom it may concern:

Be it known that I, SAMUEL EDWARD MOORE, a citizen of the United States, and a resident of Harrisburg, in the county of Dauphin and State of Pennsylvania, have invented a new and useful Improvement in Index-Drawers; and I do hereby declare the following to be a full, clear, and exact description thereof.

10 My invention pertains to filing devices, and relates especially to filing devices of the kind which are generally known as vertical filing drawers. In the ordinary construction of vertical filing drawers, as now generally 15 to be found on the market, the objection is present that the material filed in the drawer has a tendency to do one of two things,—either it tends to fall over, when the drawer is not filled, or the rear follower not moved 20 up tightly; or, if the drawer is completely filled, or the rear follower is moved up tightly, the material tends to work itself out of place, and individual units of the filed material are difficult to withdraw. Moreover, if the material has been properly filed, 25 it is necessary to release the follower before a unit can be removed; and, usually, this release of the follower is not in itself sufficient, it being necessary, generally, to move along 30 the units of the filed material, so as to loosen such material at the part where the unit is to be removed.

It is the principal object of this invention to eradicate the disadvantages referred to 35 above, and to provide a vertical filing drawer in which the units of material will always be positioned properly so that they can readily be examined, and in which any desired units can readily be removed at will.

40 It is a further object of the invention to economize in respect to the capacity of the drawer, and so to construct the drawer that the material therein will stay in place without any tendency for the same to be forced 45 out of proper position when the drawer is filled to capacity.

It is another object of the invention to attain the above results without materially increasing the cost of production of the filing 50 drawer. And other and further objects of the invention will appear from the following specification, taken in connection with the appended claims.

By way of example, I have described in the following specification and shown in the 55 accompanying drawings, one form of vertical filing drawer in which my invention may be embodied. I wish it clearly understood, however, that the invention may be embodied in other forms and that changes may be 60 made in the form described and shown without exceeding the scope thereof as defined in the appended claims.

Referring now to the drawings:

Figure 1 is a side elevation of a vertical 65 filing drawer constructed in accordance with my invention, part of the side guide being broken away, to display the socket for receiving the lower separator-strips;

Fig. 2 is a perspective view of the same; 70

Fig. 3 is a perspective view of one of the separator-strips; and

Fig. 4 is a perspective view of a modified form of separator-strip.

Like reference characters refer to like 75 parts throughout the following specification, and the several figures of the drawing.

Referring now to the drawings, the filing drawer consists of a front 10, sides 11, bottom 12, and a back 13. Upon the sides 11 are 80 provided guide-supports 14, which coöperate with the ordinary guides in the drawer-cabinet when the drawer is pushed out or pulled in by means of the handle 15. Within the drawer, there is provided the usual follower 85 16, which may be moved forwardly and rearwardly in accordance with the amount of material which is present in the drawer. As thus far described, the drawer is of a form which is well known on the market. 90

In carrying out my invention, I provide the sides 11 of the drawer with a plurality of slots 17 which extend a short distance downward from the top edges thereof. In the drawing, two of these slots are shown, 95 one for each of the top separator-strips; but more can be provided, in accordance with the number of separator-strips which are to be used. In each pair of the slots 17 is mounted a separator-strip 18, which 100 is of a length substantially equal to the outside width of the drawer. Each of the separator-strips is bent over, at its end, to form lugs 19. When the separator-strips are put into position in the slots 17, these 105 lugs 19 engage the outer faces of the sides

11, and thereby retain the separator-strips in position.

Disposed vertically below the slots 17 are sockets for the lower separator-strips.

- 5 Each of the sockets consists of a slot 20, similar to the slots 17. The portion of the drawer-side immediately above each of the slots 20 is cut away, however, so as to form an aperture 21. The lower separator-strips 10 22 are similar to the upper separator-strips 18, and, like them, are provided with end lugs 22^a. The end lugs 20 of the separator-strips 22 can readily be pushed through the apertures 22 whereupon the separator-strips 15 22 can be made to engage in the slots 20, with the end lugs 22^a engaging the outside of the drawer-sides.

It will be seen that the construction described above requires very little modification of the ordinary vertical filing drawer, and is exceedingly inexpensive; moreover, the separator-strips, when in position, take up no appreciable space between the units of filed material. It will be observed, further, that the separators support the contents of the drawer a great deal more evenly than can be the case with the ordinary constructions now on the market; moreover, they do not interfere with the use of the follower. The provision of the lower separator-strips prevents the movement of the bottom parts of the filed units, which might take place even though the top parts were properly held in place.

- 35 When material of the ordinary width is being filed, the top separator-strips, being exceedingly thin, will not be visible. For use in cases where the material to be filed is especially narrow, I may use, in place of 40 the top separator-strips 18, separator-strips 23 of the kind shown in Fig. 4. In this case, the separator-strips are provided with a downwardly extended central portion 24, against which the narrow units of filed material will readily rest. The separator-strips 45 23 are provided with end lugs 25 similar

to the lugs 19 on the strips 18 referred to above.

Having thus fully described my invention what I claim as new and desire to secure 50 by Letters Patent is:

1. The combination with a filing drawer including a pair of sides, of a relatively narrow spacing member extending across the drawer, adjacent the top thereof, said member comprising a bar having its ends bent to form locking lugs, said bar being removably associated with said sides and locked against accidental lengthwise or side- 55 wise movement.

2. The combination with a filing drawer including a pair of sides, of a relatively narrow spacing member extending across the drawer, adjacent the top thereof, said member comprising a U-shaped bar removably mounted in sockets formed in said sides, the sides of said U-shaped bar being adapted to abut the external surface of said drawer sides to prevent sidewise movement.

3. The combination with a filing drawer 70 including a pair of sides, of a relatively narrow spacing member extending across the drawer, adjacent the top thereof, said member being removably associated with said sides, and a second spacing member below said first-named member and removably associated with said sides.

4. The combination with a filing drawer, including a pair of sides having oppositely disposed slots in the top edges thereof, and 80 having oppositely disposed sockets below said slots, of a relatively narrow spacing member extending across said drawer and engaging said slots, and a second spacing member extending across said drawer and 85 engaging said sockets.

In testimony whereof, I the said SAMUEL EDWARD MOORE, have hereunto set my hand.
SAMUEL EDWARD MOORE.
